TOY SUSPENSION RAILWAY SWITCH

Arthur J. Di Stasi, Trenton, N. J.

Application August 15, 1955, Serial No. 37,476

Term of patent 14 years

(Cl. D34—15)

Fig. 1

Fig. 2

Fig. 1 is a perspective view of a toy suspension railway switch embodying my new design; and

Fig. 2 is an elevation of the side substantially opposite that of Fig. 1.

I claim:

The ornamental design for a toy suspension railway switch, substantially as shown and described.
